UNITED STATES PATENT OFFICE.

JOSEPH SUMMA, OF NEW YORK, N. Y.

DESIGN FOR AN ORNAMENTAL LAMP-SHADE.

54,339.

Specification for Design.

Patented Dec. 23, 1919.

Application filed August 5, 1919. Serial No. 315,550. Term of patent 7 years.

To all whom it may concern:

Be it known that I, JOSEPH SUMMA, a citizen of the United States, residing at New York city, in the county of New York and State of New York, have invented a new, original, and ornamental Design for an Ornamental Lamp-Shade, of which the following is a specification, reference being had to the accompanying drawings, forming a part thereof.

The figure is a perspective view of the ornamental lamp shade, showing my new design.

I claim:

The ornamental design for an ornamental lamp shade as shown.

JOSEPH SUMMA.
